UNITED STATES PATENT OFFICE.

ROWLAND HUNT, OF LONDON, ENGLAND.

BOX OR CARTON FOR HOLDING ELECTRIC LAMPS AND OTHER FRAGILE ARTICLES.

Application filed September 28, 1923. Serial No. 885,491.

To all whom it may concern:

Be it known that I, ROWLAND HUNT, a British subject, residing at 130 Shacklewell Lane, Hackney, London, E. 8., England, 5 have invented certain new and useful Improvements in a Box or Carton for Holding Electric Lamps and Other Fragile Articles, of which the following is a specification such as will enable others skilled in the art to 10 which it appertains to make and use the same.

This invention relates to a box or carton for electric lamps or other fragile articles and has more particularly to do with the 15 means for supporting the lamp in the carton in such a manner that it is safely protected and the ends of the lamp are substantially centred in the carton and preferably held within the ends thereof so as not 20 to be liable to fracture.

Cartons of this type are well known and have been made of rectangular form with extensions of the sides turned inwardly to form the supports for the lamp but hitherto 25 these turned in extensions have separate flaps on the sides.

According to my invention that end of the box which is to receive the glass end of the lamp is made with unseparated extensions 30 of the sides of the box said unseparated extensions being so creased and bent that they are capable of being turned inwardly to form a support for the lamp. The method of bending is such that a strong 35 but resilient support is provided for the lamp.

The outer edges of the extensions may be 40 of any desired shape and the corners where the extensions join the sides may be cut out to facilitate bending, such cutting being common where several folds radiate from one point.

For the cap end of the lamp I may use any suitable folding flaps or extensions but 45 I prefer to use approximately triangular flaps from one side of each of which a curved piece is removed leaving a curved edge which will fit to both the metal cap and the adjoining part of the glass as herein- 50 after described.

An example of my invention is shown in the accompanying drawings in which:

Fig. 1 shows the blank from which the box or carton is made.

Fig. 2 is a view of the cap end of the box 55 and shows a lamp therein and held by three of the flaps, one flap being left open.

Fig. 3 is substantially a cross sectional view on the line 3—3 of Fig. 2 and shows by dotted line the position taken by the 60 lamp in the box.

Fig. 4 is a view of that end of the box which is to receive the glass end of the lamp.

In this example the blank comprises the sides 1, 2, 3 and 4 and the flange 5 by which 65 the sides 1 and 4 are joined together by using an adhesive. Each of these sides has a separate flap extension, 6, 7, 8 and 9 respectively and adapted to fit to the cap end of the lamp.

The other ends of the sides are continued in unseparated extensions 10, 11, 12 and 13 and these form the main feature of my invention in that the extensions are continuous or non-separated and are so creased and 70 folded that they can be turned inwardly to form a support for the lamp.

Each of these extensions is bent along two lines as indicated at *a* and *b* and they are also folded between each other on lines 80 *c*. This folding divides each extension in three parts 14, 15 and 16. The part 15 rests against the inner faces of the sides and the parts 14 and 16 project inwardly towards the centre of the box as seen in Figs. 3 and 85 4 and so that their curved edges form an appropriately shaped support for the rounded end of the lamp. The parts 15 have extensions 17 which increase the area 90 of support for the glass of the lamp, these extensions are optional.

The flaps 6, 7, 8 and 9 are adapted to be turned in one after the other to fit around the cap end of the lamp and are preferably turned in before the lamp is inserted. When 95 the lamp is pushed into the box through the said flaps they will spring back and the curved recess 18 in each flap will get a good hold against both the edge of the cap as seen at 19 in Fig. 3 and against the adjoining glass as seen at 20.

To facilitate folding the extensions particularly if the material of the blank is thick portions may be cut out as indicated by dotted lines at *a*.

What I claim is:—

A box to hold an electric lamp comprising four integral sides each of which has

an extension at one end said extensions being integral with the sides and unseparated from each other, each extension being divided into three parts by creases in the extensions and each extension bent inwardly on the creases into the box to form a support for one end of a lamp, said sides each

having at its opposite end means for holding the other end of the lamp.

In witness whereof I have hereunto set my hand.

ROWLAND HUNT.

Witness:

HENRY FAIRBROTHER.
